[57] CLAIM

The ornamental design for a chair, as shown and described.

DESCRIPTION

FIG. 1 is a perspective view from the front and to one side of the chair.

FIG. 2 is a side elevational view of the chair of FIG. 1. The other side of the chair is the same with the exception of the chair controls.

FIG. 3 is a front elevational view of the chair of FIG. 1.

FIG. 4 is a rear elevational view of the chair of FIG. 1.

FIG. 5 is a top plan view of the chair of FIG. 1.

FIG. 6 is a perspective view from the front and to one side of a second embodiment of the chair of FIG. 1. The vertical length of the backrest is shorter than the chair of FIG. 1.

FIG. 7 is a side elevational view of the chair of FIG. 6. The other side of the chair is the same with the exception of the chair controls.

FIG. 8 is a front elevational view of the chair of FIG. 6.

FIG. 9 is a rear elevational view of the chair of FIG. 6; and,

FIG. 10 is a top plan view of the chair of FIG. 6.

1 Claim, 4 Drawing Sheets

FIG.1.

FIG.2.

FIG. 3.

FIG. 4.

FIG. 5.

FIG. 6.

FIG. 7.

FIG. 8.

FIG. 10.
